EARTH MOVING DEVICE

Roy E. Choate, Waldo E. Rodler, and William I. Leech, Cedar Rapids, Iowa, assignors to La Plant-Choate Manufacturing Co. Inc., Cedar Rapids, Iowa, a corporation of Delaware

Application September 5, 1933, Serial No. 688,178

1 Claim. (Cl. 37—144)

This invention relates to earth moving devices and has particular relation to devices in which a scraper blade is mounted for pivotal movement in front of a tractor or like prime mover.

5 In devices of the character with which we are now concerned a pair of frameworks are pivotally attached, one on each side of a tractor, to the crawler track sub-frames thereof, and a scraper blade is attached to the front ends of these side frames. An actuating mechanism for raising and lowering the rear ends of the frames to correspondingly lower and raise the scraper blade is mounted at the rear of the tractor.

It has been found that the torque or turning effort necessary to raise and lower the scraper blade may compress the springs, by which the tractor is supported on the sub-frames, to an undue extent, thus sometimes causing breakage of these springs, or of the scraper blade supporting and actuating mechanism, or other parts of the tractor.

After considerable study of this problem we have reached the conclusion that the undue compression of the springs which support the tractor on the sub-frames is caused by the reaction set up by the hydraulic jack which actuates the frame raising and lowering mechanism. We have found that, if the reaction set up in the jack by pushing the piston rod in and out is conveyed to sub-frames of the tractor, undue compression of the tractor supporting springs is avoided.

We have, therefore, devised a means for conveying the reactive forces set up in the hydraulic jack directly to the sub-frame of the tractor, and in this way have avoided the difficulties above-mentioned.

A general object of our invention is to provide means for conveying certain forces set up in a plow actuating mechanism to members which are not harmed by such forces.

45 A more specific object of our invention is to provide in an earth moving device a linkage system for conveying the reactive force of a plow actuating mechanism to the sub-frame of the tractor.

Another object of our invention is to provide guide means for guiding the side frames of an earth moving device of the type here considered.

Another object of our invention is to provide 50 means whereby undue compression of the tractor supporting springs is avoided.

Other and further features and objects of our invention will be more apparent to those skilled in the art upon a consideration of the accompanying drawing and following specification, wherein is disclosed an exemplary embodiment of the invention, with the understanding, however, that such changes may be made therein as fall within the scope of the appended claim with- 55 out departing from the spirit of the invention.

In said drawing:

Figure 1 is a side view in perspective of a tractor to which a scraper blade, blade-supporting side frames, and a blade actuating mechanism constructed according to our invention 5 have been attached, and

Figure 2 is a quartering view in perspective of a portion of the track, the track supporting sub-frame, a hydraulic jack, and a jack supporting linkage constructed according to our invention. 10

We are here principally concerned with the means by which reactive forces acting on the jack are transmitted to the sub-frame of the tractor, in order to "by-pass" these forces around the tractor supporting springs. We are, therefore 15 only incidentally concerned, at this time with the scraper blade, scraper blade mounting, side frames, and the side frame actuating shaft and levers. A more detailed description of these parts is given in a co-pending application by 20 Herbert H. Pearson, filed August 18, 1932, Serial Number 629,297, Patent Number 1,961,011 on earth moving devices, and a co-pending application by Roy E. Choate and Waldo E. Rodler on earth moving devices, filed May 9, 1932, Serial 25 Number 610,194, Patent Number 2,030,352.

Referring to the drawing, there is shown at 16 generally, a tractor having a sub-frame or track frame 11, on which the tractor is resiliently mounted, and wheels 12 and track belt 13 for supporting the sub-frame. 30

The tractor is supported with relation to the sub-frames 11 by means of coil springs or the like (not shown) in order that shocks or blows on the sub-frames will not be transmitted to the 35 tractor.

One of the stiffening or supporting members of the sub-frame 11 is a longitudinally-extending channel member 14, and the wheel bearings, indicated generally at 16, are attached to this channel member 14. 40

A pair of triangular side-frame members, indicated generally at 17, are pivotally attached, one on each side of the tractor, to the mid-point of the channel members 14, as by means of brackets 18 on the channel members. 45

The triangular side-frame members are each comprised of a long top member 19, a forwardly projecting channel member 21, and a rearwardly projecting channel member 22, with members 19 and 21 joined at their front end by means of a plate 23, and at the rear ends by means of a cap 24. The mid-point of the frame members is stiffened by means of a plate 26. 50

The lower or forward end of the member 22 is provided with a pair of brackets 27 and 28 having means for engaging a cross shaft 29, which in turn is journaled in the brackets 18. The scraper blade 31 is fastened to the front ends of the side frame members 17 and this scraper 55

blade is suitably curved and provided with universal joints in order that it may be moved to any desired position.

A cross-shaft 32 extends across the rear of the tractor, and a bifurcated lever arm 33 is attached to the outer end of the shaft 32 so that when pressure is applied to the piston rod 34 the lever arm 33a is moved to rotate the shaft 32 and thus rotate the lever arm 33b. Rotation of the lever arm 33b in one direction or the other causes a corresponding movement of the rear ends of the side frames 17 in a corresponding direction by reason of the connecting links 36.

The piston rod 34 is moved in and out by means of a hydraulic jack, the cylinder of which is indicated at 37. Fluid for actuating the piston of the hydraulic jack is introduced into the jack by means of the hose connections 38 and 39. It is apparent that if fluid is introduced into the jack through the hose connection 39 the piston rod 34 will be pushed outwardly to rotate the lever 33 in a counter-clockwise direction to draw down the rear end of the side frames 17 and thus raise the scraper blade. When fluid is introduced into the jack through the hose 38 a reverse movement of the parts of the device occurs and the blade 31 is lowered, or may even be forced downwardly by the hydraulic jack.

It is apparent that when hydraulic pressure is applied to the jack 37 the piston rod 34 is forced outwardly or inwardly, and a corresponding force or reaction is set up in the cylinder of the hydraulic jack. This reactive force usually acts in a substantially horizontal plane and drives the mounting of the jack forwardly or rearwardly, thus at times causing the tractor to pivot about at substantially its mid-point to compress the tractor supporting springs. It is, of course, very desirable to avoid this last named condition and this is one of the main objects of our invention.

In order to avoid undue compression of the tractor supporting springs, and undue stresses in other parts of the tractor, we have devised a means for transferring the reactive force set up in the jack by the actuation of the scraper blade manipulating means, directly from the jack to the sub-frame and running gear.

One means for obtaining this result is illustrated in the drawing. In this device trunnion bearings 42 are provided at the rear end and on top of the platform, fender or running board 41, and a lever arm or link, comprised of a channel member 43, extends forwardly from, and is pivotally attached to, the trunnion bearings 42. Up-struck trunnion brackets 44 are secured to the lever arm at an intermediate point thereof at a position along the length of the arm which is so chosen that least movement of the tractor occurs when the scraper blade is being manipulated. The hydraulic jack cylinder 37 is pivotally supported by these trunnion brackets 44 in order to permit the cylinder to pivot as the arm 33a rotates. The pivot points of the cylinder 37 on the link 43 may be at any point along these respecting members. A rub iron plate 46 is secured to the outermost of the trunnion brackets 44 and acts in cooperation with a plate 47 on frame members 19 and 22 as a guide to prevent "weaving" or side-motion of the side frame members.

The free end of the lever arm or link 43 is

operatively engaged to the sub-frame channel member 14 by means of a ladder-like yoke 48. This yoke 48 is provided with a bracket member 49 at its upper end in order that the yoke may be engaged to the lever arm 43 as by means of the pivot pin 51. A cross-member 52 aids in stiffening the yoke member.

The lower end of the yoke member 48 is pivotally attached to the channel members 11 and 14 by means of a rub iron bracket indicated at 52. This rub iron bracket is recessed as indicated at 53 in order that it may be secured to the channel members 11, as by means of bolts 54, and the outer face of the rub iron bracket is flat in order that it may cooperate with a rub plate 56 which is fastened to the members 19 and 21 of the side frame members and thus act as an additional guiding means for the side frame members to take any transverse or lateral forces set up in the scraper blade. The rub iron bracket 52 is provided with up-struck lugs 57 at the upper portion thereof, in order that the yoke 48 may be pivotally attached thereto, as by means of pivot pins 58.

The inner lower end of the yoke 48 is attached to the inner portion of the sub-frame 11 by means of a second bracket 52a which is of the same construction as the bracket 52 previously described, but which is fastened to the sub-frame in reversed position.

It is apparent that the reactive forces set up in the jack and particularly at the jack cylinder are transmitted directly to the sub-frame of the tractor and thence to the ground, thus avoiding compression of the tractor supporting springs and avoiding breakage of the tractor parts. Furthermore it is apparent that simple means have been provided for guiding the side frame members of the scraper blade manipulating mechanism.

It is obvious that the reactive forces in the jack and other parts may be transmitted to the ground by other means or that they may be transmitted to some part of the tractor where the force can do no harm. These and other modifications may be made by those skilled in the art without departing from the spirit and scope of our invention as set forth in the appended claim.

We claim as our invention:

In an earth moving device including a tractor and running gears for the tractor, a side frame pivotally mounted on the running gears and extending substantially the length of the tractor and projecting in front thereof, a plow blade mounted on the front end of the side frame, a cross shaft pivotally mounted at the rear of the tractor and having a lever arm fixed thereon, a link for connecting the lever arm on the cross shaft with the rear end of the side frame, a hydraulic jack and a support for the jack comprising a platform pivotally mounted on the rear portion of the tractor and extending forwardly therefrom and a link for connecting the free end of the platform to the running gear of the tractor, the jack being pivotally mounted upon the platform and operatively connected with the lever arm on the cross shaft.
